UNITED STATES PATENT OFFICE.

HENRY MARTIN, OF DUNCAN, PENNSYLVANIA.

IMPROVEMENT IN DRILLING-MACHINES.

Specification forming part of Letters Patent No. **138,570**, dated May 6, 1873; application filed February 21, 1873.

To all whom it may concern:

Be it known that I, HENRY MARTIN, of Duncan, in the county of Allegheny and State of Pennsylvania, have invented a new and Improved Portable Drilling-Press, of which the following is a specification:

My invention consists of a cylindrical standard having a base-plate adapted to be bolted or clamped on a bench, platform, or other support, on which standard is a horizontal arm capable of shifting up and down and swinging around, which carries a sliding head and an adjusting-screw to shift the head toward or from the standard; and the sliding head carries a vertical feed-screw with a socket in the lower end, in which the upper end of the hand-drill brace is centered to hold it and feed the drill, the whole comprising a simple and cheap substitute for the common ratchet-drill and its adjuncts, by which the work can be done many times faster than with the ratchet.

Figure 1 is a side elevation of my improved machine, and Fig. 2 is a plan view.

Similar letters of reference indicate corresponding parts.

A represents the standard, which consists of a strong round rod or tube of metal. B is the base-plate, to which the standard is firmly secured at the lower end; and it has slotted or elongated bolt-holes C by which to be bolted on a table or platform or the metal piece to be drilled. The base-plate is also adapted for securing the standard to the support by clamps D. E is the horizontal arm for supporting the feed and centering screw F. It is

fitted on the standard at one end by a hole in it, through which the standard passes snugly, but so that the arm can be shifted up and down and turned around; and it is provided with a binding-screw, G, by which it is fastened whenever it is required. H is the head-block, in which the screw F is mounted. It is fitted on the arm E in ways I to slide along the arm for adjusting the screw over the work, and provided with an adjusting-screw, K; also with clamp-screws L for binding it firmly against the arm, so as not to shake or tumble while holding the drill-crank. This feed-screw has a little conical socket, M, at the lower end, in which the conical end N of the top of the drill-crank O is fitted to be centered, confined, and adjusted to feed the drill as the work progresses.

This contrivance affords a very simple press for hand-drilling, capable of adjusting the drill in various and wide ranges.

Having thus described my invention, I claim as new and desire to secure by Letters Patent—

The tube A, slotted plate B C, arm E, end-socketed centering-screw F, sliding head-block H, and screws G K L, combined as described, said parts being put together and taken apart, as set forth, so as to make an easily-portable hand-drill.

HENRY MARTIN.
